G. L. ELLIS

Des. 162,636

BATHROOM UTILITY HOLDER

Filed Oct. 17, 1950

FIG' 2

FIG' 1

George L. Ellis ^{INVENTOR.}

UNITED STATES PATENT OFFICE

162,636

BATHROOM UTILITY HOLDER

George L. Ellis, Lawndale, Calif.

Application October 17, 1950, Serial No. 12,608

Term of patent 14 years

(Cl. D4—3)

To all whom it may concern:

Be it known that I, George L. Ellis, a citizen of the United States, residing at 4627 West 159th Street, Lawndale, State of California, have invented a new, original, and ornamental Design for Bathroom Utility Holders, of which the following is a specification, reference being had to the accompanying drawing, forming a part thereof.

Fig. 1 is a front elevational view of a bathroom utility holder, showing my new design; and

Fig. 2 is a top plan view thereof.

I claim:

The ornamental design for a bathroom utility holder, as shown.

GEORGE L. ELLIS.
